CONTAINER

Egon Mauser, Kolin-Bayenthal, Germany, assignor to Mauser Kommandit - Gesellschaft, Kolin - Ehrenfeld, Germany

Filed Dec. 12, 1956, Ser. No. 627,934

Claims priority, application Germany Dec. 16, 1955

4 Claims. (Cl. 220—63)

The invention relates to containers and more particularly shipping vessels, such as barrels or the like used for the transportation and storage of corrosive, taste-sensitive and valuable filling materials.

In order to dispense with the use of expensive materials, namely aluminum, copper, pure nickel, non-corrosive steel, metal alloys and the like, containers have been produced which consist of an inner sleeve or shell and outer bracing elements. The outer bracing elements replace the previously employed outer container, but, it was ascertained that the outer bracing elements (steel reinforcements) were not sufficient to protect the inner container made of expensive material from external destructive actions. Hence, the wall of the inner container had to be made stronger, and, the cost of the same exceeded substantially the production costs of the outer container. To the extent that enclosures of synthetic material, cardboard, rubber and the like were used for a thin-walled inner container or shell, the wall thickness of the outer envelope or enclosure, in view of the high resistance required by the entire container was such that the increased cost of manufacture was prohibitive. This is especially true of enclosures of a synthetic material as suitable synthetic materials are too expensive respecting purchase and processing for containers.

Furthermore, a container has been heretofore provided which consists of a barrel having a metal or synthetic material lining and the foil is in the nature of a bag which is inserted into the outer container.

Outer containers made of steel do not, however, satisfy the requirements since in filling and dispensing corrosive materials, contact of the filling material with the outer container cannot be avoided. This results in a premature destruction of the outer container by a corrosive action and the inner container or lining fails to protect the assembly against damage as cracks and the like are easily formed therein.

The above and other objectionable characteristics are overcome according to the present invention. To produce the present invention, there is provided an inner sleeve or shell, preferably of corrosion-resistant metal or homogeneous synthetic material and the wall thickness or cross section is quite thin. Bracing reinforcements of a less expensive or non-corrosive resistant substance which are subjected to external mechanical stresses are provided for the inner sleeve and such reinforcements are in the nature of head rings and annular hoops by means of which the container can be rolled along a supporting surface. A layer of synthetic material is applied, preferably in a liquid state or in a state permitting kneading throughout the entire assembly. After this latter layer has set or hardened, a rigid and insoluble joint or union is effected between the reinforcement and the inner sleeve or shell thereby attaining the required mechanical resistance necessary by the container.

It is also possible to produce a container having equivalent characteristics by placing the inner sleeve, preferably centrally in a mold and the intermediate space bounded

by the mold and the inner sleeve is filled with a liquid material, such as Silumin and synthetic materials.

In using metal or steel reinforcements in connection with the inner sleeve, the cavities of such reinforcements can be filled with suitable material prior to the application to the inner sleeve or shell. The boundary surface of the filler material adjacent the container is adapted to the particular shape of the container. The reinforcements are preferably applied to the inner sleeve by the use of an adhesive, and, thereafter, the outer synthetic layer is applied so that the layer covers all of the areas of the assembly.

Moreover, it is also possible that the reinforcement can be first placed on the inner sleeve or shell and the cavities of the reinforcement filled by pouring an adhesive filler therein. After the filler is set, it joins the reinforcement and inner sleeve.

Another embodiment includes the concept that the filled head reinforcement, the bottom bunghole and the wall are applied to the inner sleeve, and, the outer sleeve or shell of synthetic material is then secured. At the mid-zone and at both sides, the synthetic coating is wider and thicker thereby achieving the additional rigidity.

To avoid deformation of the inner sleeve or shell, prior to or during application of the synthetic material, or during pouring, the inner sleeve is filled with a gaseous or liquid medium, and, safety means regulating the pressure are employed.

Between the reinforcement and the inner sleeve, a layer of synthetic material in a liquid state or a state allowing kneading, may be applied so that after setting, a rigid, insoluble medium results.

The synthetic material can be applied as an outer sleeve in one or more layers and intermediate the layers, filler or bracing layers of mineral fiber, wrapping paper, fibrous substances, textiles or wire netting can be arranged.

The synthetic material can be colored by the addition of the desired color medium and the drying or setting can be accelerated by a convenient heat treatment.

Between the thin-walled inner sleeve or shell and the reinforcements, a synthetic substance can be positioned, and, this is especially true of containers in which the reinforcements are hollow rolling hoops and head hoops. In addition, reinforcements such as a bunghole flange, name plates, advertising plates and the like can be united by the use of synthetic materials without the employment of other means.

The outer wall of the container can be bulged, and, hollow hoops having a filler can be provided at the ends and the side wall with the inner sleeve and reinforcements secured together by an outer sleeve of synthetic material. At the upper end and in the mid-zone thereof, the synthetic layer is thickened and surrounds the bunghole unit carried by the inner sleeve, and an annular ring also cooperates with the bunghole unit to additionally retain such unit.

The lower end of the inner sleeve or shell can be arched and surrounded by an arched synthetic coating.

Adjacent to the bunghole unit carried by the side wall of the inner shell, the outer synthetic layer is thickened to compensate for the bunghole unit and adapt the same to the outer contour of the container.

Other objects and advantages of the invention will become more readily apparent to one skilled in the art from a study of the ensuing description and the appended claims.

Reference will be had to the accompanying drawings forming part of this application and wherein are shown preferred embodiments of the invention and in which:

Fig. 1 is a fragment of a container in vertical cross section of one form of the invention.

Figs. 2 and 3 are fragmental views in vertical cross section of further forms of the invention.

Fig. 4 is a vertical sectional view of a fragment of the upper end of a container illustrating the mode of reinforcing the bung-hole unit.

Fig. 5 is a vertical sectional view of a barrel having bulged side walls constructed in accordance with the invention.

Fig. 6 is a fragment of a barrel with bulged side walls showing in vertical cross section, a further form of the invention and,

Fig. 7 is a vertical sectional view of yet another form defined by an inner shell and a cast outer wall.

As shown in Fig. 1, a container C is defined by an inner sleeve of shell 1 of very thin cross section and the shell is provided with an annular hollow hoop 2 and hollow end or head parts 3. The hoop 3 allows the container to be easily rolled on its side along a surface while the end parts permit the ready movement in the vertical or substantially vertical position.

Intermediate the inner shell 1 and the end parts 3, there is first applied a synthetic material 4 and this material layer defines a joint therebetween. An outer relatively thin-walled layer of synthetic material 5 is then applied to the assembly, with the material either in a liquid state or a state allowing kneading. When the layer 5 has set or hardened, it surrounds the sleeve or shell 1 together with the hoop 2 and the end parts 3 thereby holding the respective parts together.

Together with the reinforcements and the inner sleeve 1, the synthetic layer 5' includes a substantial portion of the supporting member, and, this portion can be increased in the manner shown in Figs. 2 and 3. More specifically, this is effected by arranging between two or more synthetic layers 5' and 7, an intermediate layer or layers 8 of the required thickness, and, such intermediate layer can be fibrous material, paper, cardboard, mineral fiber and the like. In addition, less expensive material, such as wire netting of fine or coarse mesh can be employed for the intermediate layer.

In Fig. 4, there is illustrated a manner in which a bung-hole unit is attached to the container. It will be seen that an internally threaded ring 9 of the same material as the shell 1 is reinforced by a bung-hole ring 10 which is covered by a layer of synthetic material 11 thereby permanently connecting the parts with the inner shell 1, and, the connection is improved by interposing a synthetic layer between the sleeve 1 and the ring 10.

Fig. 4 further shows how a name plate or an advertising plate 12 can be simultaneously secured to the assembly.

It will be appreciated that the container is very sturdy, presents a smooth surface, and, if desired, the synthetic layer can be colored to suit requirements of the purchasers. Furthermore, valuable material is saved, and, depending on the use of the container, a considerable range of synthetics can be employed. The synthetics may be either very hard or elastic, such as PVC or polyester bases.

In Fig. 5, there is depicted a barrel B wherein the side wall is bulged, and, is of a type commonly used for malt beverages, such as beer and ale. In this form, a thin-walled inner shell 13 of metal or synthetic material is provided at its ends with hollow reinforcing rings 14 and the cavities of the rings contain a filler material 15. The inner shell 13 and the rings 14 are entirely covered by a layer or sleeve 23 of synthetic material and in the mid-zone of the assembly, the layer is thickened to provide a band 16 and adjacent to the ends, the layer is thickened to form bands 17 which are slightly less in height than the central band 16. The dimensions of the bands 16 and 17 are determined in accordance with the stresses which will be imposed on the barrel, and, the wide band 16 is primarily used in connection with beer barrels.

A synthetic coating 18 at the upper end of the barrel is of greater thickness at the central part, and a bung-hole unit 19 is arranged at the central part. A reinforcing ring 20 surrounds the bung-hole unit and serves to anchor the unit in proper position.

A bung-hole unit 21 is provided for the side wall of the barrel, and, it will be noted that the inner shell 13 is planar adjacent the unit 21 as indicated at 22 so that at this area, the outer synthetic layer is materially thickened at 23 in order to compensate for the length of the bung-hole unit 21. The lower end of the inner shell 13 is arched, and, the outer surface thereof is covered with a synthetic layer 24 and is of a thickness corresponding to the load imposed on the lower end of the barrel.

In Fig. 6 is illustrated a modified container in which inner shell 13' is provided with reinforcing steel hoop-like members spaced along the side wall and such members are identified 25 and 26. The cavity of the member 25 located at the central zone of the wall is filled with suitable filler material 28, and, the cavities of the members 26 positioned on opposite sides of the member 25 contain similar filler material 27. Outer wall 23' of synthetic material includes the metal hoop-like members 25 and 26.

Fig. 7 shows a vessel V having a thin-walled inner shell 29 provided with recesses 30 for bung-hole units. Outer sleeve 31 is formed by casting and is such a thickness as to satisfy the requirements which are made on the vessel. Hoops 32 and end projections 33 are preferably formed during casting or in any other suitable manner and the end of the bung-hole recess 30 is surrounded by casting flange 34. In order to strengthen the hoops 32 of the outer shell 31, reinforcing inserts 35 of steel and the like may be cast in the shell.

The present invention is not to be confined to any strict conformity with the showings in the drawings, but, may be changed or modified so long as such changes or modifications mark no material departure from the salient features of the invention as set forth in the appended claims.

I claim:

1. A container for materials such as corrosive, taste-sensitive and like substances comprising an inner shell of corrosion-resistant metal having a wall thickness dimension insufficient to provide the desired rigidity for the container, a plastic layer permanently secured to the outer surface of the inner shell and being of such thickness that the interconnected inner shell and plastic layer define a unitary container having the desired rigidity, metal reinforcements positioned on the outer surface of the inner shell with said plastic layer permanently securing the reinforcements in the proper position on the shell periphery, each metal reinforcement being provided with a cavity and a filler material filling the cavities.

2. A container for materials as claimed in claim 1, in which said inner shell is formed with bulged side walls and the plastic layer adjacent the middle of the shell is of thicker cross-section thereby providing a rolling surface for the container.

3. A container for materials as claimed in claim 1, further including a bung-hole unit for one of the ends of the inner shell, the layer surrounding the bung-hole unit being relatively thick in cross-section for securing the bung-hole unit to the inner shell, and a cup-like ring surrounding the bung-hole unit for further securing the bung-hole unit to the container end.

4. A container for materials as claimed in claim 1, further including a bung-hole unit located at the middle of a side wall of the shell, and the plastic layer at the middle portion of the shell being of such thickness as to be flush with the outer end of the bung-hole unit for securing the unit to the shell.
